C. MAGERKURTH,
PORTABLE METAL PLANING AND FINISHING MACHINE,
APPLICATION FILED MAY 17, 1915.

1,170,454.

Patented Feb. 1, 1916.

UNITED STATES PATENT OFFICE.

CHARLES MAGERKURTH, OF LOS ANGELES, CALIFORNIA, ASSIGNOR OF ONE-HALF TO
EMELINE MAGERKURTH, OF LOS ANGELES, CALIFORNIA.

PORTABLE METAL PLANING AND FINISHING MACHINE.

1,170,454.

Specification of Letters Patent.

Patented Feb. 1, 1916.

Application filed May 17, 1915. Serial No. 28,802.

To all whom it may concern:

Be it known that I, CHARLES MAGERKURTH, a citizen of Peru, residing at Los Angeles, in the county of Los Angeles and State of California, have invented new and useful Improvements in Portable Metal Planing and Finishing Machines, of which the following is a specification.

My invention relates to new and useful improvements in electrically operated portable metal planing and finishing machines suitable for finishing plane surfaces of metals and especially of brass castings though it is also adapted to operate on other material besides metal, such as wood or stone.

It is an object of my invention to construct a machine which may be moved by hand over the surface of the metal or other material to be operated on in the same manner as a flat iron is moved in every direction across the work supported on a stationary bench or work support.

Another object of the invention is to construct a machine of the kind referred to which is compact, simple of construction, positive in its operation, and having novel means for adjusting the operating tool in relation to the work, whereby a greater or smaller portion of the surface is operated on and the depth of the cut is regulated.

Another object of this invention is to provide a machine of the kind described having a tool rotatably mounted and driven by an electric motor and having adjustable bottom and side gage members controlling the operative surface of the tool. The machine is also provided with means for adjusting the distance with which the operating tools project between the adjustable bottom gage plates, whereby the amount of material to be planed or ground off may be controlled.

My invention consists in the construction and arrangement of parts hereinafter described and claimed.

In the drawings which form a part of this specification: Figure 1 is a side view of the apparatus. Fig. 2 is a top plan view thereof. Fig. 3 is a front end view with an auxiliary gage plate attached to the bottom thereof. Fig. 4 is a side view of the operating tool. Fig. 5 is an end view thereof. Fig. 6 is a fragmentary view in perspective of a modified form of the operating

tool. Fig. 7 is a vertical cross section taken on line 7-7 of Fig. 1.

The apparatus consists of a solid metal frame 10 provided with ribs 11, as shown, to secure greater strength. It is made of suitable size so as to be easily operated, being not much larger than an ordinary carpenter's plane. On the upper part of the posterior end of the frame is a handle 12 and adjacent thereto is a motor 14 of any preferred construction with suitable electric connections. A pulley 15 mounted on the shaft of the motor drives the countershaft 16 provided with pulley 17 by means of band 18 or any other suitable connection. Rigidly mounted on shaft 16 in any suitable manner is an emery wheel 19 which is positioned in an opening 20 somewhat larger than the emery wheel, as shown. The width of the emery wheel is the same as that of the metal frame 10. Shaft 16 is supported at opposite sides of the emery wheel in a pair of arms 21-22. The arms are pivoted at their ends, which are adjacent to the motor, to a bolt 23 passing transversely through the frame, and are provided at their centers with suitable roller bearings in which shaft 16 is journaled. The other ends of the arms are formed with eyes through which a bolt 24 passes transversely through the frame. This bolt is threaded at either end and provided with nuts 25.

The adjustment is effected as follows: A rotatable vertical threaded bolt 26, provided with a thumb nut 27 at its upper end, and pivoted to the frame 10 at its lower end, is positioned in a vertical channel 26' in the frame. A slotted ear 27' engages the upper part of bolt 26 and allows for the slight oscillatory movement thereof, due to the arc of the circle which bolt 24 describes in its vertical movement. This bolt 26 engages a threaded bore in the middle of bolt 24. By rotating bolt 26, bolt 24 will be vertically raised or lowered thereby adjusting the forward ends of arms 21 and 22 and the rotatable tool carried thereby in vertical relation. A slot 28 is provided in the frame allowing such vertical adjustment and the eyes on the forward ends of arms 21 and 22 are made of a size sufficient to provide a good bearing surface against the frame on either side of the slot 28. By tightening nuts 25 the rotating tool will be securely

held in its adjusted vertical position. The lower part of the frame is provided with a pair of longitudinal slots 10' extending horizontally on opposite sides thereof, as shown in Fig. 7. A pair of bottom gage members consisting of open metal boxes 29 and 30 of rectilineal cross section are provided with inwardly extending flanges 45 at the upper end thereof which engage the longitudinal grooves referred to. The ends of boxes 29-30 which are adjacent to the operating tool are cut away to conform to the curvature thereof and are spaced therefrom. The anterior box 29 and the posterior box 30 extend from the front and rear, respectively, to the operating tool and are spaced from each other leaving a free space or slot 31 between them through which the operating tool extends. In order to retain the boxes in their adjusted position a screw 32 is countersunk on one side thereof and extends transversely into a correspondingly threaded socket 33. By tightening screw 32 the boxes or bottom gage members will be clamped in their adjusted position.

By turning bolt 26 the emery wheel may be made to extend through slot 31 and beyond the boxlike gage members 29 and 30 for any desired distance and by longitudinally adjusting the boxlike gage members 29-30 the length of the slot 31 may be varied, as desired. These two adjustments will control the thickness of the material to be removed and the area of the operative surface of the rotating tool.

The apparatus is especially suitable for planing off brass castings. The plane surfaces of brass castings are rough and uneven and must be planed or filed down. My improved apparatus will quickly and perfectly plane off or grind down the plane surfaces of such castings and will also satisfactorily operate where the castings are provided with vertical flanges or steps. The vertical surface of such flange may be ground or planed simultaneously with the horizontal surface with my machine. For this purpose I have provided a pair of lateral gage plates 35 and 36 which are slidably mounted on the face of the boxlike gage members 29-30 on opposite sides thereof, the bottom of said lateral gage plates being flush with the bottom of the boxlike gage members. Slotted vertical straps 37 extending from the lateral gage plates and provided with screws 38 which engage a corresponding threaded bore in the frame, provide means for vertical adjustment thereof. If it is desired to operate on the vertical face of a flange as well as on the horizontal plane surface meeting said vertical face, the lateral gage plate adjacent to the flange is vertically adjusted by means of the straps 37 and screws 38. The lateral bottom part of the emery wheel which is now exposed by reason of the vertical adjust-

ment of the lateral gage plate, is now free to engage and operate on the vertical face of the flange while the periphery of the wheel engages the horizontal plane of the casting.

The apparatus is also suitable to plane an edge of a casting or other material. In order to guide the apparatus along an edge a guide plate 39 in the shape of an angle iron is attached to the bottom of the boxlike gage members by means of screw bolts 40 which engage corresponding threaded bores in the lateral gage members 36. The horizontal member of said guide plate is cut away just below slot 31, forming a concave shaped depression 46, which permits the emery wheel 19 to extend through slot 31 below the bottom gage members without interfering with said guide plate. The lateral gage plates 35, 36 have similar cut away portions adjacent to the emery wheel in order to provide a clearance space allowing the emery wheel to rotate without contacting with said lateral guide plates.

I prefer to construct the emery wheel with slots 41 cut across the operating surface at an angle, as shown in Figs. 4-5. The corners of the emery wheel adjacent to these slots are preferably rounded off. The efficiency of the emery wheel is greatly increased by such construction.

It is obvious that any other rotatable tool suitable for operating on a plane surface of metal or like material may be substituted for the emery wheel. In Fig. 6 I have shown a fragmentary view in perspective of another metal working rotatable tool. On the periphery of the wheel cutting members 42 are detachably secured to the rim of said wheel in dove-tailed relation, as shown. These cutting members have sharp horizontal edges and are provided with vertical grooves on their frontal faces to facilitate their cutting action. These members can easily be removed and resharpened.

Operation: The motor will rotate the operating tool at a suitable speed, which for the emery wheel is 3500 revolutions per minute. The tool is vertically adjusted through the slot 31 by means of bolt 26. The length of this slot is controlled by the longitudinal adjustment of said bottom gage members. The operator places one hand on the handle and the other on the top part of the forward end of the machine and moves the same over and across the plane surface to be operated on. The operating tool will quickly remove the metal to the desired extent, the shavings of the metal being thrown and removed through the channel formed between the frame of the machine and the bottom gage members. The surface operated upon will be perfectly smooth and plane, due to the fact that the bottom gage members control the depth of the cut of the operating tool.

It is not necessary that the motor furnish-

ing power for operating the rotating tool be an integral part of the apparatus. The motor, or any other source of power, may be mounted at any convenient place and power 5 may be transmitted to the tool by means of belts and pulleys, carried on movable and pivoted arms, provided with a universal joint, which allows free movement of the planing and finishing machine across the 10 work to be operated on. I have not shown such power transmission because they are no part of my invention, though it is to be understood that my invention may be used in connection with such power transmission de- 15 vices if desired.

I do not limit myself to the specific construction of my device as shown and described. Various changes within the spirit 20 of my invention and the scope of the claims 20 will suggest themselves to those skilled in the art. For instance, it may be desirable to construct the flanges 45 of the box-shaped gage member 29 and the corresponding grooves 10' in which said gage member is 25 slidably mounted, at an angle extending from the rear upwardly to the operating tool. This construction will effect that when the gage member is adjusted outwardly, not only will slot 46 be increased in length but 30 gage member 30 will also be lowered a slight distance below the plane of the front gage member 29 but maintaining a parallel relation thereto. The rotating tool is lowered so that its operating surface at its lowest point 35 is in horizontal alinement with gage member 29. Another advantage of this construction is that it will allow the operating tool to cut away the amount of material desired, leaving a perfectly plane surface, which 40 could not be produced if the operating surface of the tool is lowered and extends through the slot 46 beyond the plane faces of the gage.

I claim:

45 1. In a portable planing and grinding machine, a frame, a pair of arms, each arm being pivoted at one end to said frame and provided with an eye at the free end, a horizontal shaft journaled in the center of said 50 arms, means for rotating said shaft, a tool removably mounted on said shaft, a pin threaded at the ends passing through the eyes of said arms and provided with a centrally threaded bore, a rotatable threaded 55 rod swiveled to said frame, said rod passing through the bore of said pin and being provided with a thumb nut at its upper end, nuts on the ends of said pin for locking said arms in adjusted position to the frame, a pair of horizontally adjustable box-shaped 60 gage members open at their ends and slidably mounted at the bottom of said frame, said members being spaced from each other, whereby a slot is provided through which 65 the operative part of said tool extends,

means for locking said members in adjusted position, a pair of lateral gage plates mounted on opposite sides of said gage members, means for vertically adjusting said plates, and a detachable longitudinal guide plate 70 extending at right angles from the bottom of said gage members.

2. In a portable planing and grinding machine, a frame, a pair of arms, each arm being pivoted at one end to said frame and 75 provided with an eye at the free end, a horizontal shaft journaled in said arms, means for rotating said shaft, a tool removably mounted on said shaft, a pin threaded at the ends passing through the eyes of said arms, 80 means for vertically moving said pin, means for locking the free ends of said arms to said frame, a pair of horizontally adjustable gage members open at their ends slidably mounted at the bottom of said frame and 85 spaced from each other, whereby a slot is provided through which the operative part of said tool extends, means for locking said members in adjusted position, a pair of lateral gage plates mounted on opposite sides 90 of said gage members, and means for vertically adjusting said plates.

3. In a portable planing and grinding machine, a frame, a pair of arms, each arm being pivoted at one end to said frame, a horizontal shaft journaled in said arms, means for rotating said shaft, a tool mounted on said shaft, means for vertically adjusting the free ends of said arms, a pair of horizontally adjustable box-shaped gage members open at their ends and slidably mounted at the bottom of said frame, said members being spaced from each other, whereby a slot is provided through which the operative part of said tool extends, a lateral gage plate 105 mounted on one side of said gage members, and means for vertically adjusting said plate.

4. In a portable planing and grinding machine, a frame, a pair of arms, each arm being pivoted at one end to said frame, a horizontal shaft journaled in said arms, means for rotating said shaft, a tool mounted on said shaft, means for vertically adjusting said arms, a pair of horizontally adjustable gage members movably mounted at the bottom of said frame, said members being spaced from each other, whereby a slot is provided through which the operative part of said tool extends, means for locking said members in adjusted position, and a lateral gage plate adjustably mounted on one side 115 of said gage members.

5. In a portable planing and grinding machine, a frame, a pair of arms, each arm being pivoted at one end to said frame, a shaft 125 journaled in said arms, means for rotating said shaft, a tool mounted on said shaft, means for simultaneously adjusting said arms in vertical position, a pair of horizontally adjustable gage members spaced from 130

the bottom of said frame and from each other, whereby a slot is provided through which the operative part of said tool extends, and a lateral gage plate adjustably mounted on one side of said gage members.

6. In a portable planing and grinding machine, a frame, a horizontal shaft, means for rotating said shaft, a tool mounted on said shaft, vertically adjustable bearings in which 10 said shaft is journaled, a pair of horizontally adjustable gage members movably mounted at the bottom of said frame and spaced therefrom, said members being spaced from each other, whereby a slot is 15 provided through which the operative part of said tool extends, and means for locking said members in adjusted position.

7. In a portable planing and finishing machine, a frame, a shaft, an abrading tool on 20 said shaft, means for rotating said shaft, ad-

justable bearings in which said shaft is journaled, said frame being provided with a slot through which the operative part of said tool extends, and adjustable means for controlling the size of said slot.

8. In a portable planing and grinding machine, a frame, a horizontal shaft, an abrading tool on said shaft, means for rotating said shaft, vertically adjustable bearings in which said shaft is journaled, and a plurality of horizontally adjustable gage members movably mounted at the bottom of said frame and spaced therefrom, one of said members being also vertically adjustable, whereby a slot is provided through which the operative part of said tool extends.

In witness that I claim the foregoing I have hereunto subscribed my name this 10th day of May, 1915.

CHARLES MAGERKURTH.
